UNITED STATES PATENT OFFICE.

ROBERT M. MCGRATH, OF LAFAYETTE, INDIANA.

CAR-AXLE BOX.

SPECIFICATION forming part of Letters Patent No. 334,540, dated January 19, 1886.

Application filed September 26, 1885. Serial No. 178,225. (No model.)

To all whom it may concern:

Be it known that I, ROBERT M. MCGRATH, a citizen of the United States, residing at Lafayette, in the county of Tippecanoe and State 5 of Indiana, have invented certain new and useful Improvements in Car-Axle Boxes, of which I do declare the following to be a full, clear, and exact description, reference being had to the accompanying drawings, forming part of 10 this specification.

In the construction of car-axle boxes as at present commonly practiced it is customary to provide the box upon its outer side with a lid or slide, by opening which the interior of 15 the box can be readily reached for the purpose of restoring the lubricant, examining the condition of the brasses, and the like. It is very desirable that the lid of the box when closed should form with the body a very tight 20 joint, so that the ingress of dust will be avoided, and an effective construction of box-lid heretofore devised for this purpose is that wherein in a lid, formed slightly tapering or wedge-shaped, slides within correspondingly-tapered 25 vertical grooves in the walls of the box.

In this class of devices it is important that the lid be so connected with the body of the box that there will be no danger of its being accidentally displaced or lost, either by reason 30 of the movement of the car or by the carelessness of the inspector in hastily opening the box; and the object of my present invention is to provide improved means whereby the accidental loss or displacement of the lid will be 35 avoided.

To this end my invention consists in providing the lid with a stop device of improved construction, as hereinafter described, which, while permitting the lid to be freely raised, 40 will prevent its becoming accidentally disconnected from the box.

Figure 1 is a view in vertical longitudinal section, the box-lid being shown closed in full lines and open by dotted lines. Fig. 2 is a view in vertical longitudinal section, illustrating the manner of slipping the box-lid into its place. Fig. 3 is a view in vertical transverse section on line $\alpha\alpha$ of Fig. 1.

A designates the body of the axle-box, in 50 the flanged side walls of which are formed the tapering vertical grooves a , having near their tops the seats a' . Within the grooves a of the

box fits, in a manner free to slide, the lid or cap B, which is tapered, as shown, to correspond with the grooves a , so that the weight 55 of the lid when closed will cause it to form with the box a very tight joint. The seats a' at the tops of the grooves a serve as rests for the lid when raised to open the box. Upon the inner side of the lid B is formed the recess C, within which, on a suitable pin, c, is journaled, in a manner free to swing, the stop or pawl D. The lower hooked end, d, of this pawl, when in its normal position, as seen in Fig. 1, projects a sufficient distance beyond 60 the inner face of the lid to engage with the upper edge of the seat a' , formed at the top of the box, and thus guard the lid against accidental displacement or withdrawal from the grooves a of the box. The recess C is prefera- 65 bly formed of such size, and the journal-pin c is placed in such position therein that the pawl D can be turned into the upper portion of the recess, as seen in Fig. 2, when the lid is to be placed into the grooves a of the box, or is 70 to be purposely drawn therefrom. The outer wall of this recess serves as a handle for lifting the lid.

From the foregoing description the operation will be seen to be as follows: In order to 75 permit the lid B to be placed within the vertical groove a of the box, the stop or pawl D will be turned into the upper portion of the recess C, so as to allow the pawl to avoid the front edge of the seat a' at the top of the box. 80 When the lid B is thus placed on the box, the free end of pawl D will swing downward and will rest against the bottom of the recess C. When the lid B is raised to permit the inspection of the journals or renewal of the piping, 85 the hooked end d of the pawl D will engage with the edge of the recess a' at the top of the box, and will prevent the withdrawal of the lid from the vertical groove a , and the lid can be retained in its raised position by placing 90 its bottom corner in the seat a' at the tops of the vertical grooves. The pawl D serves not only to prevent the withdrawal of the lid from the box when the lid is hurriedly lifted, but also securely guards against all danger of the 95 accidental displacement of the lid by reason of the motion of the car.

It will be readily understood that the precise details of construction above set out may

be varied without departing from the spirit of my invention.

Having thus described my invention, what I claim as new, and desire to secure by Letters

5 Patent, is—

1. In a car-axle box, the combination, with the body of the box, of a lid provided with a stop or pawl pivoted to swing at right angles to the plane of the lid, substantially as described.

10 2. In a car-axle box, the combination, with the body of the box, of a lid provided with a stop or pawl pivotally held on the inner side thereof and entirely within the body of the

15 box, substantially as described.

3. In a car-axle box, the combination, with the body of the box, of the lid having the recess C therein, and a stop or pawl, D, pivoted within said recess, substantially as described.

4. In a car-axle box, the combination, with the body of the box, of a lid having pivotally held on its inner side the pawl D, provided with a hooked end, d, substantially as described. 20
